UNITED STATES PATENT OFFICE.

JOSEPH HIGGINSON AND HUBERT ARUNDEL, OF STOCKPORT, ENGLAND.

LIQUID-FUEL-SUPPLY SYSTEM OF INTERNAL-COMBUSTION ENGINES.

1,311,695.

Specification of Letters Patent. Patented July 29, 1919.

Application filed January 19, 1918. Serial No. 212,737.

To all whom it may concern:

Be it known that we, JOSEPH HIGGINSON and HUBERT ARUNDEL, subjects of the King of Great Britain and Ireland, and residents 5 of Sovereign Works, Stockport, in the county of Chester, England, have invented certain new and useful Improvements Relating to Liquid-Fuel-Supply Systems of Internal-Combustion Engines, of 10 which the following is a specification.

This invention relates to liquid fuel supply systems of internal combustion engines of the type in which the fuel is drawn from a low level tank or vessel to an intermediate vessel from which it is discharged by gravity to the engine carburetor.

Our invention comprises the improved arrangement of the means for controlling the suction or vacuum connection and also, 20 if desired, of the atmospheric connection, of the intermediate vessel.

Referring to the accompanying explanatory drawings:-

Figure 1 is a view of an apparatus constructed in one convenient form in accordance with our invention.

Fig. 2 shows a modified arrangement of apparatus and Fig. 3 is a detail view of the continuously operating suction and air control valve.

The same reference letters in the different views indicate the same or similar parts.

Referring to Fig. 1, we employ a vacuum pump as indicated at *a* as the source of suction for the intermediate vessel *b* and provide a valve as *b'* upon the suction pipe *c* which is positively opened at intervals so as to place said pump *a* and vessel *b* in communication with one another for drawing 30 fuel into the vessel from the low level tank (not shown) through the fuel pipe *d*. The said valve *b'* may be of any convenient form such as a plug cock actuated by an arm *e* which is engaged by a projecting 40 piece *f* on the spur wheel *g* driven from the pump shaft.

It will be understood that when the fuel level in the vessel *b* rises above a predetermined height, the float *g* closes the valve 50 *p* and prevents the suction from the pump *a* acting in said vessel. At the same time, atmospheric pressure is re-established in said vessel through the atmospheric connection *i*. Fuel therefore flows by gravity past the 55 valve *r* and so to the engine carburetor (not shown).

We may also, if desired, provide a timed valve actuated from the pump shaft or a connected part, for controlling the atmospheric connection *i* of the intermediate vessel *b*, the opening movement of the air and suction valves being regulated so that when one valve is open the other is closed and vice-versa. The air valve indicated at *j* is, in the illustration, actuated by an arm *k* from a 60 projecting arm *m* on the spur wheel *g*. The valve *j* is returned to its open position and the valve *b'* to the closed position by springs *n* and *o* respectively.

We do not limit ourselves to any particular form or arrangement of the timed suction and air valves aforesaid, but may modify same to suit requirements. With the mechanically operated valve arrangement, it is only necessary to provide a float 70 controlled valve within the vessel *b* to prevent flooding of such vessel. In the Fig. 1 arrangement, such float controlled valve *p* isolates the vessel *b* from the source of suction when the liquid level in *b* rises unduly. 80

In the arrangement shown at Fig. 2, the float controlled valve *p* acts to close the liquid fuel inlet *d* to the vessel *b* so that fuel cannot be drawn into the latter when the valve is closed. The rotary valve *b'* in this 85 case is in the form of a plug cock controlling a suction port *c'*, an air port *i* and a port leading by way of the pipe *e* to the vessel *b*. It will be seen that the one pipe *e* in this example serves for both air and suction. The cock *b'* is rotated by differential gears 1, 2, 3, 4 (as shown) from the pump crank shaft so as to give a slow movement 90 to the cock. The float *g* works on a stem guided at *g'* in the end of the connection 95 from the pump *a*. The valve *p* is carried by the arm *p'*.

Having now described our invention what we claim as new and desire to secure by Letters Patent is:-

1. In liquid fuel supply apparatus for internal combustion engines, in combination, a vessel into which fuel is drawn by suction and from which it is discharged by gravity, a float controlled valve in said vessel regulating the amount of fuel drawn into the vessel, a source of vacuum, positively timed means controlling communication between said source of vacuum and said vessel, and means restoring atmospheric pressure in the 110 intervals between the suction periods, as set forth.

2. In liquid fuel supply apparatus for internal combustion engines, in combination, a vessel into which fuel is drawn by suction and from which it is discharged by gravity, 5 a float controlled valve in said vessel regulating the amount of fuel drawn into the vessel, a vacuum pump, an atmospheric connection, and positively timed means controlling communication between said pump, 10 said atmospheric connection and said vessel, as set forth.
3. In liquid fuel supply apparatus for internal combustion engines, in combination, a vessel into which fuel is drawn by suction 15 and from which it is discharged by gravity, a float operated valve in said vessel acting to control the fuel inlet to said vessel, a vacuum pump, an atmospheric connection, and positively timed means controlling communication between said pump, said atmos- 20
- pheric connection and said vessel, as set forth.
4. In liquid fuel supply apparatus for internal combustion engines, in combination, a vessel into which fuel is drawn by suction 25 and discharged by gravity, a float operated valve in said vessel acting to control the fuel inlet to said vessel, a vacuum pump, an atmospheric connection, and a continuously rotating plug cock controlling communication 30 between said pump, said atmospheric connection and said vessel, as set forth.

In testimony whereof we have signed our names to this specification in the presence of two subscribing witnesses.

JOSEPH HIGGINSON.
HUBERT ARUNDEL.
